DESIGN FOR A MASTICATOR FOR FRUITS, VEGETABLES, OR THE LIKE

Charley Stuart, San Francisco, Calif.

Application July 29, 1946, Serial No. 132,095

Term of patent 14 years

(Cl. D44—1)

To all whom it may concern:

Be it known that I, Charley Stuart, a citizen of the United States, residing in the city and county of San Francisco, State of California, have invented a new, original, and ornamental Design for Masticator for Fruits, Vegetables, or the like, of which the following is a specification, reference being had to the accompanying drawing, forming a part thereof.

Fig. 1 is a perspective view of the masticator for fruits, vegetables, or the like, showing my design;

Fig. 2 is a side view of the masticator; and,
Fig. 3 is a plan view of the masticator.

I claim:

The ornamental design for a masticator for fruits, vegetables, or the like, as shown.

CHARLEY STUART.
